UNITED STATES PATENT OFFICE

158,909

BUBBLING CANDLE LAMP

Joseph J. Suring, New York, N. Y., assignor to
Noma Electric Corporation, New York, N. Y., a
corporation of New York

Application November 17, 1947, Serial No. 142,581

Term of patent 7 years

(Cl. D48—20)

To all whom it may concern:

Be it known that I, Joseph J. Suring, a citizen of the United States, residing at New York, Westchester County, and State of New York, have invented a new, original, and ornamental Design for a Bubbling Candle Lamp, of which the following is a specification, reference being had to the accompanying drawing, forming part hereof.

In the drawing:

Fig. 1 is a side elevational view of a bubbling candle lamp showing my new design;

Fig. 2 is a top plan view thereof, and

Fig. 3 is a sectional view taken on line 3—3 of Fig. 1.

I claim:

The ornamental design for a bubbling candle lamp, substantially as shown.

JOSEPH J. SURING.
